(57) **CLAIM**

The ornamental design for a four leaf clover straw cover, as shown and described.

DESCRIPTION

FIG. 1 is a perspective view of a first embodiment of the four leaf clover straw cover showing my new design.

FIG. 2 is a rear perspective view of a first embodiment of the four leaf clover straw cover.

FIG. 3 is a front view of a first embodiment of the four leaf clover straw cover.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a perspective view of a second embodiment of the four leaf clover straw cover.

FIG. 10 is a rear perspective view of a second embodiment of the four leaf clover straw cover.

FIG. 11 is a front view of a second embodiment of the four leaf clover straw cover.

FIG. 12 is a rear view of FIG. 11.

FIG. 13 is a left side view of FIG. 11.

FIG. 14 is a right side view of FIG. 11.

FIG. 15 is a top view of FIG. 11; and,

FIG. 16 is a bottom view of FIG. 11.

The broken lines illustrate portions of the four leaf clover straw cover that form no part of the claimed design.

1 Claim, 16 Drawing Sheets
